Primary Examiner—Jeffrey Asch

(57) **CLAIM**

The ornamental design for pneumatic tool, as shown and as described.

DESCRIPTION

FIG. 1 is a perspective view of pneumatic tool showing my design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof with attachments shown in broken lines; and,

FIG. 9 is a perspective view thereof with attachments shown in broken lines.

The broken line showings of attachments in FIGS. 8 and 9 are for illustrative purposes only and form no part of the claimed design.
